ELECTRIC ARC LAMP

Max Körting and Felix Werner, Leipzig, Germany

Application February 1, 1935, Serial No. 4,447
In Germany February 1, 1934

9 Claims. (Cl. 176—76)

Our invention relates to carbon feeding mechanism for electric arc lamps having rod shaped electrodes, as commonly used in search lights, head lights, projecting apparatus and kindred appliances, wherein the feed of one of the rod shaped electrodes, hereinafter briefly called "feeding electrode", is accomplished by a gear positively operated by a motor in such manner, that the luminous arc or the incandescent crater is automatically kept in proper working condition and at its appropriate place relatively to the reflector of the search light or the condensor-lens of the projecting apparatus concerned.

15 Our invention relates more especially to carbon feeds, wherein the feeding electrode is intermittently advanced while being rotated. With a carbon feed of this type, known in the art, the carbon is intermittently fed by a feeding mechanism comprising pawls, which while revolving are reciprocated in the feeding direction and engage the carbon except during their backward movement, viz. when the pawls are returned into their initial position and release the carbon, over 20 which they slide.

25 One of the principal objects of this invention is to provide a structurally improved carbon feed of the type set forth, in which the feeding electrode is continuously rotated, namely is kept rotating also while the feed gear is on its backward stroke.

Another object of the invention is to simplify the manipulations necessary in replacing—while the feed gear works—the feeding electrode by a 30 fresh electrode, and also in controlling and readjusting by hand the feed and the accurate position of the feeding electrode relatively to its mate and to the other vital parts of the arc lamp.

Still other objects will become incidentally apparent hereinafter to those skilled in this art.

The nature and scope of the invention are briefly outlined in the appended claims and will be more fully understood from the following specification taken together with the accompanying drawings in which

50 Figs. 1—3 show diagrammatically in a small scale arc lamps for search lights and projecting apparatus fitted with an electrode feeding mechanism designed according to this invention.

55 Fig. 4 is a side elevation partly in section of an electrode-feeding mechanism designed according to this invention.

Figs. 5—7 are cross sections taken through the feeding mechanism shown in Fig. 4 on lines V—V, VI—VI, VII—VII respectively;

Fig. 8 is a side elevation of a structurally modified reciprocating mechanism to be used in connection with this invention.

The electrode feeding mechanism designed according to this invention essentially consists of 5

(I) A support having two upright walls 1, 1', through apertures of which the rod shaped feeding electrode is to pass in the direction of arrow a, and in which a hollow rotary shaft 3 is journaled;

(II—coupling 2) Means attached to said support and hollow shaft for uniformly revolving said electrode around its axis;

(III) A feed gear attached to and cooperatively associated with said coupling means, for intermittently feeding said electrode in axial direction, while being rotated, and

(IV) Releasing means under the control of the operator attached to and cooperatively associated with said feed gear for throwing the latter out of engagement with the electrode concerned.

In the embodiment of the invention shown in Figs. 4 and 5 said coupling means comprise: A driving shaft 20 coupled with a suitable prime mover (not shown), a secondary shaft 20', a train of gear wheels 21—21', 22—5 cooperatively interconnecting the said driving shaft, secondary shaft and hollow shaft 3; three gripping rollers 24, 24', 24'' having sharp circumferential edges for engagement with the feeding electrode 2 and being mounted on said rotary shaft 3, so as to be carried around therewith in a circular path; slots longitudinally extending in said shaft, through which the said rollers project, the latter being so arranged with respect to the feeding electrode, that the latter is free to move in axial direction but is positively rotated jointly with the said rollers 24, 24', 24''.

The trunnions of said gripping rollers are 40 journaled in slotted cheek plates 4, 4'' attached to gear wheel 5 and are resiliently interconnected by springs 25, 25'.

In the embodiment of the invention shown in Figs. 4—5 the feed gear concerned consists of 45 a gripping mechanism, which comprises:

Three pawls 14, 14a, 14b, which are slidably fitted in slots 13 of the hollow shaft 3 so as to be carried around thereby in a circular path and to be free to move relatively in an axial and a radial direction; actuating means for bodily moving said pawls 14, in an axial and a radial direction to said hollow shaft 3; the said actuating means comprise a housing 8 having coni-

- cal inner walls 16 for cooperation with corresponding conical faces provided on said pawls.
- A spring 15 for resiliently keeping in engagement said pawls and housing; the latter is slidably mounted on said rotary hollow shaft 3 and is coupled therewith by a pin and slot gear 6, 1 so as to be rotated jointly with said shaft and to be free to be reciprocated relatively thereto in an axial direction.
- 10 Means are provided for reciprocating said housing 8 at intervals; said reciprocating means comprise a pin 10 rearwardly projecting from said housing 8; a rotary sleeve 11 loosely fitting over said rotary hollow shaft 3 and having a crown cam provided thereon for cooperation with said housing and pin; a spring 9 for resiliently keeping in engagement said housing 8 and sleeve 11; and means for rotating said sleeve 11 in the same direction as housing 8 but at a different 20 ratio of speed.
- In the embodiment of the invention shown in Figs. 4, 6, 7 said rotating means comprise a couple of spur gear wheels 12—23, driven by the auxiliary shaft 20' and having a ratio of gear 25 auxiliary shaft 20' and having a ratio of gear wheels 5—22, being slightly larger than that of gear wheels 5—22.
- Since housing 8 and the pawls 14 engaging the electrode 2 rotate at a ratio of speed slightly exceeding that of the crown cam the pin 10 will periodically travel up the inclined face of said 30 cam with the result that the housing 8, pawls 14 and electrode 2 are slowly advanced in the feeding direction.
- After the pin 10 has passed the crest of said crown cam the housing 8 is returned in its initial 35 position shown in Fig. 4 by spring 9, thereby incidentally disengaging the pawls 14, which in turn cease to firmly grip the electrode 2.
- Our experiments have shown that an effective 40 gripping contact of the pawls with the electrode 2 is insured by providing said pawls with triangularly shaped teeth 14', which are one-sidedly shaped, pointing in the feeding direction like those of so-called rip-saws.
- In order to enable the operator to conveniently 45 replace the feeding electrode 2 by a fresh one, or to re-set by hand the movable electrode into its proper position, or to stop the feeding motion, while the feeding mechanism works, releasing means are provided, which comprise: a 50 collar 17, co-axially fitted on said sleeve 11 and being adapted to throw said pawls 14, 14a, 14b out of engagement with their housing 8; and means under the control of the operator for moving said collar to and fro in axial direction; 55 said operating means comprise a grooved flange projecting from said collar 17, a yoke 18 engaging said flange and a spring loaded handle 19 attached to said yoke and being slidably fitted in the support 1'.
- 60 Various changes and modifications may be conveniently made in the design and structural details of electrode feeding mechanism of the improved type described above, without substantially departing from the spirit and the salient ideas of our invention.
- 65 As diagrammatically indicated in Fig. 8 instead of a rotary sleeve formed with a crown cam at its front face for cooperation with the housing 8 for reciprocating the latter a groove 26 may be formed thereon for cooperation with a 70 spring loaded forked lever 30, pivoted at 27 and engaging said groove; and a rotary cam 28 may be provided for imparting a rocking motion to said lever 30.
- 75 What we claim is:—
1. In a carbon feed for electric arc lamps a rod shaped electrode, a feed gear for intermittently feeding the electrode, a rotary coupling for continuous rotation of said electrode, while being fed, and means for rotating said coupling, said feed 5 gear comprising a longitudinally movable rotary hollow shaft enclosing said electrode, a gripping mechanism cooperatively associated with said hollow shaft, so as to rotate therewith and be free to be reciprocated in an axial direction relatively to said shaft, and actuating means for engaging and disengaging said gripping mechanism and the electrode.
  2. Carbon feed for electric arc lamps having the features outlined in claim 1, in which said 15 gripping mechanism comprises a support, a rotary hollow shaft carried by said support, slots formed longitudinally within said hollow shaft, and a plurality of pawls slidably fitted within said slots for cooperation with the electrode, said 20 pawls being formed with triangular teeth, which are one-sidedly directed in the feeding direction comparable to those of a rip saw.
  3. Carbon feed for electric arc lamps having the features outlined in claim 1, in which said 25 gripping mechanism comprises a support, a rotary hollow shaft carried by said support, slots formed longitudinally within said hollow shaft, and a plurality of pawls slidably fitted within said slots 30 for cooperation with the electrode,—said actuating means comprising a housing cooperatively associated with said rotary hollow shaft so as to be rotated therewith and axially reciprocated thereon, and means for reciprocating said housing, the latter enclosing said pawls and being provided 35 with conical inner walls opposed to corresponding conical faces provided on said pawls, and with a spring for resiliently keeping in engagement said housing and pawls.
  4. Carbon feed for electric arc lamps having the 40 features outlined in claim 1, in which said gripping mechanism comprises a support, a rotary hollow shaft carried by said support, slots formed longitudinally within said hollow shaft, and a plurality of pawls slidably fitted within said 45 slots for cooperation with the electrode, said actuating means comprising a housing cooperatively associated with said rotary hollow shaft so as to be rotated therewith and axially reciprocated thereon, and means for reciprocating said 50 housing, the latter enclosing said pawls and being provided with conical inner walls opposed to corresponding conical faces provided on said pawls, and with a spring for resiliently keeping in engagement said housing and pawls,—said 55 reciprocating means comprising a pin rearwardly projecting from said housing, a rotary sleeve loosely fitting over said rotary hollow shaft and being formed with a crown cam for cooperation with said housing and pin, a spring for resiliently keeping in engagement said housing and sleeve, and driving means for revolving said sleeve at a rate of speed different from that of the hollow shaft and housing.
  5. Carbon feed for electric arc lamps having 65 the features outlined in claim 1, in which said gripping mechanism comprises a support, a rotary hollow shaft carried by said support, slots formed longitudinally within said hollow shaft, and a plurality of pawls slidably fitted within 70 said slots for cooperation with the electrode, said actuating means comprising a housing cooperatively associated with said rotary hollow shaft so as to be rotated therewith and axially reciprocated thereon, and means for reciprocating said 75

- housing, the latter enclosing said pawls and being provided with conical inner walls opposed to corresponding conical faces provided on said pawls, and with a spring for resiliently keeping 5 in engagement said housing and pawls,—said reciprocating means comprising a pin rearwardly projecting from said housing, a rotary sleeve loosely fitting over said rotary hollow shaft and being formed with a crown cam for cooperation with 10 said housing and pin, a spring for resiliently keeping in engagement said housing and sleeve, and driving means for revolving said sleeve at a rate of speed different from that of the hollow shaft and housing,—said driving means comprising 15 a main driving shaft and two sets of gear wheels differing in their ratio of gearing and cooperatively interconnecting said main shaft with the hollow shaft and the said sleeve respectively.
- 20 6. Carbon feed for electric arc lamps having the features outlined in claim 1, in which said gripping mechanism comprises a support, a rotary hollow shaft carried by said support, slots formed longitudinally within said hollow shaft, and a 25 plurality of pawls slidably fitted within said slots for cooperation with the electrode,—said actuating means comprising a housing cooperatively associated with said rotary hollow shaft so as to be rotated therewith and axially reciprocated thereon, and means for reciprocating said housing, the latter enclosing said pawls and being provided with conical inner walls opposed to corresponding conical faces provided on said pawls, and with a spring for resiliently keeping in 30 engagement said housing and pawls,—said reciprocating means comprising a groove circumferentially formed on said housing, a spring loaded forked lever, engaging said groove, and a rotary cam engaging said lever and being adapted to 35 impart a rocking motion to the latter at intervals.
- 40 7. Carbon feed for electric arc lamps having the features outlined in claim 1, in which said gripping
- mechanism comprises a support, a rotary hollow shaft carried by said support and having slots longitudinally formed therein, a plurality of pawls slidably fitted within said slots for cooperation with the electrode, and releasing means under 5 the operator's control for throwing said gripping mechanism into and out of operation.
8. Carbon feed for electric arc lamps having the features outlined in claim 1, in which said gripping mechanism comprises a support, a rotary 10 hollow shaft carried by said support and having slots longitudinally formed therein, a plurality of pawls slidably fitted within said slots for cooperation with the electrode, and releasing means under the operator's control for throwing said 15 gripping mechanism into and out of operation,—said releasing means comprising a collar concentrically enclosing said rotary shaft and manually moved to and fro so as to throw said pawls into and out of engagement with the electrode, and 20 operating means for moving said collar in axial direction.
9. Carbon feed for electric arc lamps having the features outlined in claim 1, in which said gripping mechanism comprises a support, a rotary 25 hollow shaft carried by said support and having slots longitudinally formed therein, a plurality of pawls slidably fitted within said slots for cooperation with the electrode, and releasing means under the operator's control for throwing 30 said gripping mechanism into and out of operation, said releasing means comprising a collar concentrically enclosing said rotary shaft and manually moved to and fro so as to throw said pawls into and out of engagement with the electrode, and 35 operating means for moving said collar in axial direction, said operating means comprising a grooved flange attached to said collar, a yoke engaging said flange, and a spring loaded handle attached to said yoke.

40
